BRUSH

Edwin Rolker, Baltimore, Md.

Application August 17, 1934, Serial No. 740,347
Renewed May 13, 1936

2 Claims. (Cl. 15—192)

This invention relates to a brush which can be made in quantity at very low cost, and which is strong and serviceable. The details of the invention will be clear from the following specification taken in connection with the accompanying drawing, in which,

Fig. 1 is a perspective view of the brush;

Fig. 2 is a side view, the brush head being shown in section on the line 2—2 of Fig. 1, and, Fig. 3 is an edge view of the brush, the brush head being shown in section on the line 3—3 of Fig. 2.

Referring to the drawing, the brush head *a* comprises a tuft of bristles *1* embedded at one end in a flat oblong base *2* of vulcanized rubber. The handle *b* of the brush is composed of a wire, doubled somewhat sharply upon itself as shown at *3* and from the bend *3* the two arms *4* of the wire are bowed oppositely to form a gripping portion, said arms coming close together near the brush head, as shown at *4a*, thence diverging, as shown at *4b*, and the end portions *4c* of the handle thence extending parallel with one another into the base *2* near the ends of the latter, the ends of the arms being flattened and roughened, as indicated at *4d*, so as to interlock with the rubber base.

In making the brush, the bristles are primarily assembled in a close tuft by suitable mechanism and by cementing the coarse ends of the bristles together with rubber cement and allowing this to dry. The handle is arranged in a suitable frame with the flattened ends uppermost and projecting above the frame and a layer of raw rubber of suitable thickness to form the base is pressed downwardly over the projecting ends of the handle so that they become embedded in the rubber. The cemented end of the tuft of bristles is then pressed downwardly into the raw rubber and while the parts are in these positions and the rubber is confined at its edges to give it the required shape, the assemblage is placed in a vulcanizing oven and the base is vulcanized.

The brush is finished by placing over the base a sheet metal cap or ferrule *c* of oblong rectangular form adapted to fit closely around the edges of the base as well as against its face which forms the end of the brush head, as

shown. The part *5* of the cap which fits against the face of the base has a longitudinal slot *5a* which permits the cap to be passed downward over the handle, as indicated in dotted lines in Fig. 2, onto the base, the width of the slot being slightly greater than the diameter of the wire and the length of the slot being such that when the cap is fitted onto the base of the brush head the end portions of the slot will fit closely against the end portions *4c* of the handle. The cap, thus fitting closely around the base and against the handle ends, strengthens the connections between the handle and the base of the brush. If desired the sides of the cap may be indented slightly so as to interlock with the brush head to keep the cap from coming loose.

The handle is flattened at the bend *3*, as shown, and this strengthens the handle against lateral spreading of the arms *4* and facilitates manufacturing of the brush by preserving proper spacing of the arms until the rubber has been vulcanized.

What I claim is:

1. A brush comprising a flat oblong base of vulcanized rubber, a single tuft of bristles, substantially co-extensive with the length and width of the base, having one end embedded in said base and projecting at one side thereof, a handle projection from the opposite side of the base and comprising a wire doubled upon itself and having its ends spaced apart and embedded in the base near the ends of the latter, and a metal cap fitting closely around the edges and against the face of the base and having a longitudinal slot through which the end portions of the handle extend, the end portions of said slot fitting closely against the end portions of the handle.

2. A brush comprising a flat oblong rectangular base of vulcanized rubber, a single tuft of bristles, substantially co-extensive with the length and width of the base, having one end embedded in said base and projecting at one side thereof, a handle projecting from the opposite side of the base, said handle comprising a wire bent sharply upon itself and flattened at the bend, forming arms, the ends of said arms being spaced apart and embedded in the base.

EDWIN ROLKER.
